DETENTION WINDOW

Howard G. Pillsbury, Detroit, Mich., assignor to
Chamberlin Company of America, a corpora-
tion of Michigan

Application September 4, 1944, Serial No. 552,614

5 Claims. (Cl. 160—353)

This invention relates to detention screen guards, such as are used in hospitals, insane asylums, or other institutions for safeguarding insane or violent patients against injury or escape, by a guard that withstands either shocks produced by heavy impacts or attempts to cut or penetrate the screen with knives, screw drivers or like instruments, or any other method of attack, and which guard resembles an ordinary fly screen and avoids any appearance of restraining bars.

One object of the invention is to provide an improved guard of this kind in which the screen panel and its frame are mounted yieldingly in a support for movement in a direction normal to the plane of the panel itself and with little or no motion in said plane.

Another object is to simplify and improve the construction so as to reduce cost, while still protecting the screen against injury or damage by the patient and the patient against the effects of his own violence.

Further objects of the invention in part are obvious and in part will appear more in detail hereinafter.

In the drawings,

Fig. 1 represents an elevation of a portion of one form of guard embodying the invention, portions of the frame being broken out to expose interior parts;

Fig. 2 is a detail cross section on the line 2—2, Fig. 1;

Fig. 3 is a similar view showing the parts in the positions assumed upon impact with the screen panel;

Fig. 4 is a detail sectional view of one of the springs, the section being taken on the line 4—4, Fig. 3, and

Figs. 5, 6, 7 and 9 are detail views, corresponding to Fig. 2, and illustrating other forms of the invention; and

Fig. 8 is a view corresponding to Fig. 4 and showing the spring used in Fig. 5.

The detention guard shown in the drawings comprises a movable screen member and means for mounting it yieldably in a suitable support, such as a main frame, in such manner as to withstand successfully the usual shocks and jars to which such guards are subjected in use, such as impacts upon the screen by the hands, or by a patient attempting to dive through the screen, or by tools, such as knives or heavy objects, such as a chair or bed post.

The screen member consists of a suitable sub-frame, preferably strong and rigid, shaped to the building opening, as at a door or window, and to

which subframe is attached the screen panel. The screen panel, shown at 10, usually is made of strong woven wire with a mesh fine enough to serve as a fly screen. At the same time it must be strong enough to withstand cutting. Therefore, wire made of strong stainless steel alloy, or any equivalent therefor, is suitable. The edges of the screen panel are suitably secured in the panel- or sub-frame, which may be separate from or a part of the main frame, as will appear.

In Figs. 1 to 3, the main frame consists of two members 11, 12, of which member 11 is stationary and member 12 is movable and forms the sub-frame before referred to. The edge portions of the screen panel 10 are folded around a steel strip 13, and with said strip are firmly clamped, by the screws 14, between a solid bar 15 and a flange 16 of member 12, as shown in Fig. 2. Members 11, 12 are of generally similar form, the flanges 16 along their inner edges being offset from the general planes of said members and lying parallel to each other but spaced apart, and their outer edges being provided with flanges 17 extending normally to the planes of said members and overlapping each other. Member 11 is provided with means for attaching it to the stationary window or door frame, shown conventionally at 18, such as a flange 19 through which securing screws 20 may extend, preferably on the outside of the building opening where they are inaccessible to patients, since this window is designed as a guard against patients within the building rather than unauthorized entry from without.

Adjacent their inner and outer edges the two members are secured against separation, as by bolts 21 and pins 22 on one or both members extending through elongated slots 23 in the flanges of the other member, as shown in Figs. 2 and 6.

Members 11, 12 being spaced apart, they together form a housing enclosing a chamber 24. This contains the yielding means effective upon the screen panel. Said means may be either of the tension or compression type, depending upon the manner of mounting. In Figs. 2 and 6, the member 12, to which the screen panel is attached, is exposed to the building interior. It therefore moves outwardly and toward member 11 upon impact from within. Accordingly, at intervals around the periphery of the main frame, say every 3-4 inches, I provide springs of any suitable form. In Fig. 6 these are spiral compression springs 25a with their ends confined by pilots 26. In Figs. 2 and 4, they are leaf springs 25b of bowed form, with their arches 27 held under pins 28 and

their free ends confined to slide between small guide flanges 29.

In either case, upon application of force or impact to the inside of the screen panel, the entire screen member, including the wire panel and the subframe members 12 to which it is attached move outwardly, or in a direction normal to the plane of the screen panel, either flexing the leaf springs in Fig. 4 or shortening the spiral springs in Fig. 6. Said springs thus permit yielding motion and cushion the shock, avoiding or preventing either injury or damage to the screen itself or to the cause of the impact, such as the insane patient's arms or head.

Movable member 12, it will be noted, is so mounted in the frame as to be practically immovable in the plane of the screen panel. Thus, all impact is taken up by yielding motion of the parts in a direction normal to the screen panel, except for that slight motion necessary for free movement and to compensate for incidental slight bending of the subframe members, as will be readily understood.

The arrangements illustrated in Figs. 5 and 7 require no extended description, since they differ from the forms shown mainly in the use of tension rather than compression springs. For example, in Fig. 7 the spiral tension springs 25c have their ends secured to small brackets 30 fastened to the frame members 11, 12, of which the movable member 12 is on the outside of the building and therefore movable away from member 11 upon internal impact upon the screen. In Fig. 8 the leaf springs 25d have their opposite end portions engaged under pins 31 similar to pins 28, compelling flexure of the spring arms upon impact. Otherwise this form is like that shown in Fig. 7.

In Fig. 9, the screen panel 10 is fastened in a rigid subframe 32 mounted between an abutment flange 33 of member 12 and a spring bead member 34 which may be snapped into place, as shown, to lock its flange behind the shoulder formed by a rolled portion of the metal at 35. Insertable and removable spacers 36 may be used to fill the space back of the panel frame. The spiral spring shown is of the tension variety, as in Fig. 7, and members 11, 12 separate upon impact.

All frame members, of course, are mitered at the corners and, except for the snap in bead members 34, are also secured to each other at the corners, as by welding.

In all forms the screen panel is mounted for yield in a direction normal to its own plane, with little or no motion in its own plane. The constructions are simple to fabricate and to mount in place.

Other advantages of the invention will be apparent to those skilled in the art.

What I claim is:

1. A guard screen for windows, doors or the like, comprising a screen panel having a rigid peripherally extending subframe to which its edge portions are secured, a main frame member upon which the subframe is relatively movably mounted, and yielding means opposing relative motion between said main and subframe members in a direction normal to the plane of the panel.

2. A guard screen of the character described in claim 1, in which the main and subframes together form a housing enclosing said yielding means.

3. A guard screen of the character described in claim 1, in which the main and subframes move away from each other upon the application of force to the screen panel from the interior of the building.

4. A guard screen of the character described in claim 1, in which the main and subframes move toward each other upon the application of force to the screen panel from the interior of the building.

5. A guard screen for windows, doors or the like, comprising a screen panel having a rigid peripherally extending subframe to which its edge portions are secured, a main frame member upon which the subframe is relatively movably mounted, yielding means opposing relative motion between said main and subframe members in a direction normal to the plane of the panel, and means preventing movement of the screen panel in the main frame in a direction parallel to the plane of the panel.

HOWARD G. PILLSBURY.
